DESIGN FOR A TABLE

Karl Kipp, East Aurora, N. Y.

Application July 24, 1935, Serial No. 57,791

Term of patent 3½ years

To all whom it may concern:

Be it known that I, Karl Kipp, a citizen of the United States, residing at East Aurora, in the county of Erie and State of New York, have invented a new, original, and ornamental Design for a Table, of which the following is a specification, reference being had to the accompanying drawing, forming part thereof; and in which the figure is a perspective view of a table showing my new design.

I claim:

The ornamental design for a table substantially as shown.

KARL KIPP.
